UNITED STATES PATENT OFFICE.

FREDERICK C. ELY, OF NORTHAMPTON, MASSACHUSETTS, ASSIGNOR TO THE FLORENCE MANUFACTURING COMPANY, OF NORTHAMPTON, MASSACHUSETTS, A CORPORATION OF MASSACHUSETTS.

CARTON OR DISPLAY DEVICE.

No. 897,608.

Specification of Letters Patent.

Patented Sept. 1, 1908.

Application filed August 22, 1905. Serial No. 275,291.

To all whom it may concern:

Be it known that I, FREDERICK C. ELY, a citizen of the United States, residing at Northampton, county of Hampshire, State of 5 Massachusetts, have invented a certain new and useful Improvement in Carton or Display Devices, of which the following is a specification, reference being had therein to the accompanying drawings.

10 Many small articles, such for example as tooth brushes, toilet articles and the like, are packed for delivery to the consumer in individual boxes. These boxes are attractively designed, colored and ornamented, and the 15 display of them in show cases or in shop windows is an efficient method of calling the attention of customers to the articles which are contained within the package as well as to their quality, merits, etc. In shipping 20 the articles to the jobber or retailer, the manufacturer commonly places a dozen or some other desired number of the individual boxes in a carton which serves as a convenient package for a given number of the small 25 boxes and to protect them in shipment. When, however the individual boxes are received by the retailer, the retailer takes them from the carton in order that they may be properly displayed and ordinarily the carton 30 is laid aside or destroyed. If the carton is put aside the individual boxes are left without protection and become defaced, soiled, or impaired in appearance.

My invention affords a convenient carton 35 or package which fully protects the individual boxes during shipment and while being stored, and which in the hands of the retailer serves to display the individual boxes to prospective purchasers in the most effective 40 manner. My combined carton and display device also affords the individual boxes while being displayed protection from injury or defacement to which the goods would be subjected if the individual boxes were displayed 45 loosely.

In the drawings, I have shown the invention applied to a series of long boxes such as are used for holding tooth brushes, but it will be apparent that the device may be 50 varied according to the size, shape and number of the individual packages which it is desired to receive.

My invention will be fully understood

from the following description taken in connection with the accompanying drawings, 55 and the novel features thereof are pointed out and clearly defined in the claims at the close of this specification.

Referring now to the drawings, Figure 1 is a plan view of the package opened. Fig. 2 60 shows a package bent into a substantially circular shape to display the goods. Fig. 3 shows a package in form for mailing. Fig. 4 65 is a view of a box such as is used in connection with my improved mailing package. Fig. 5 shows a mailing package embodying my invention in a modified form, the said package being folded for mailing. Fig. 6 shows this package opened for the reception 70 of the small boxes.

Referring first to Fig. 1 there is there shown a form of combined mailing package and display device adapted to hold a dozen individual boxes C. At A is indicated the main body portion of a sheet of card board or other 75 suitable material from which my improved carton or display device is constructed. This sheet of card board A may be creased or scored at various places to facilitate bending where desired. Six of the twelve boxes 80 which the carton is adapted to contain are placed on one side, and six on the other side of a space K, which is left at approximately the middle of the sheet of card board A. This space K is substantially twice the thickness 85 of the boxes C and permits the two halves of the carton and the boxes placed on the said two halves to be folded over onto each other into the position shown in Fig. 3 without the boxes interfering with each 90 other. When in its folded position the corresponding boxes in the two spaces on each side of the space K are in registration with each other and the portion K of the backing forms the end of the carton. At one end of 95 the sheet of card board A is left a projecting flap which when the device is in its closed condition lies against the end of the boxes on both rows. At the other end of the sheet of card board A is formed another flap H which 100 is made long enough to fold around the edge of the package and is provided with a tongue I adapted to be inserted in the slit J as shown in Fig. 3, and to hold the whole firmly together so that the carton may be readily handled. The flap G just referred to serves also

105

to stiffen the mailing package while the flap H secures the whole together, and also has a further use which will be described later.

The various individual boxes C are attached 5 by any convenient means to the sheet of card board or backing A when in use. For the purpose of securing the boxes to the sheet of card board A, I find it convenient to form tongues or tucks B on each side of the said 10 sheet of card board A. These tongues or tucks are slightly tapering to facilitate their use. When in use the tongues B, B, are folded over the ends of the boxes C and tucked under the upper wall D of the box, as 15 shown in dotted lines in Fig. 1. The construction of one of these boxes C is seen in Fig. 4. If desirable, the tongues B, B, may be scored to facilitate their bending about the box as shown at E and F. It is apparent 20 that the size and shape of the tongues will vary according to the size of the boxes for which the carton is designed. Other means of attaching the individual boxes to the backing composing the body of the carton may be 25 employed if desired.

When the device is used to display the contents thereof, it may be hung up on a nail by the tongue I so that the individual boxes are displayed to the public, the parts being then 30 in substantially the position shown in Fig. 1.

It is customary to print upon the boxes C advertising matter descriptive of the nature of the goods contained in the boxes. As heretofore stated, I find it convenient to 35 print also upon each space occupied by a box C on the card A the same matter as is printed upon the corresponding face of the box, so that when a box is sold from the mailing package or display card the printing on the 40 card A comes into view and the package still appears to be full. Of course other advertising matter may be placed upon the card if desired.

If desired to display the package on the 45 counter, it is only necessary to bend the mailing package in the opposite direction to that shown in Fig. 3 and to tuck the flap G into the crevice between the end box B and the card board sheet A. It then assumes a somewhat 50 cylindrical form, as shown in Fig. 2, and rests firmly upon the base formed by the ends of the box and the edge of the card board sheet A. The boxes may be easily removed from the holder when in this form.

55 When it is desired to provide a carton for a less number of individual boxes than a dozen, I form the carton and display device after the manner shown in Figs. 5 and 6. In this form the boxes are attached to a card L 60 by tongues M, M, as in the previously described form of my invention. At one end of the card L I provide a flap N of the width equal to the thickness of one box and at the other end a covering portion O long enough to fold 65 over all the boxes. At the other end of this

portion O is a flap P and tongue Q for insertion in a slit R, in the manner already described. This package containing six boxes may be hung up for display by the tongue Q and may be printed with advertising matter 70 behind the boxes as previously described. The portion O affords an additional place for advertising matter.

It is to be noted that when the package is in its closed condition it forms substantially 75 a box and the contents of the same are wholly protected. The display package may also be made up in other shapes to contain a greater or less number of boxes if desired.

What I claim is;

1. The combined carton and display device for individual boxes comprising a sheet of cardboard upon the main portion of which the boxes are to be disposed in groups, the space between the said groups being substantially equal to the combined thickness of as many of said boxes as there are groups, the said sheet being provided with a plurality of tongues on each side equal in number to the number of boxes which the display device is 80 adapted to hold, and of greater length than the thickness of said individual boxes so as to overlap the end of the box and enter a pocket in the box, a flap at one end of the sheet adapted to be folded over the thickness of the 85 boxes when the several groups are folded together and means whereby when the sheet is folded and the several groups of boxes are folded together, the said flap may be engaged with the opposite end of the sheet.

2. The combined carton and display device for individual boxes comprising a sheet of cardboard upon the main portion of which the boxes are to be disposed in groups, the space between said groups being substantially equal to the combined thickness of as many of said boxes as there are groups, a 95 crease in said cardboard at each side of said space between the groups, the said sheet being provided with a plurality of tongues on each side equal in number to the number of boxes which the display device is adapted to hold, said tongues being transversely creased in alignment with the body portion of the 100 cardboard so that when the tongues are folded there will be no side projections, a flap on one end of the body of the card adapted to be 105 folded up against the sides of the boxes when the display device is folded and contains boxes, and a flap at the opposite end of the 110 sheet having a transverse crease along the line of the box next that end whereby said sheet may be folded over the side of the group of boxes and means whereby said flap may be engaged with the overlapping flap at the 115 other end of the sheet.

3. A combined carton and display device for individual boxes comprising a sheet of cardboard upon the main portion of which the boxes are to be disposed in groups, the 120

space between said groups being substantially equal to the combined thickness of as many of said boxes as there are groups, the said sheet being provided with a plurality of 5 tongues on each side equal in number to the number of boxes which the display device is adapted to hold, in combination with a plurality of individual boxes disposed transversely of the sheet which forms the display 10 device, said boxes being equal in length to the width of the body of the sheet, each box being in alinement with two of said oppositely disposed tongues and secured to the body of the sheet by the tongues being 15 tucked into the ends of the boxes.

4. A combined carton and display device for individual boxes comprising a sheet of cardboard upon the main portion of which the boxes are to be disposed in groups, the 20 space between said groups being substantially equal to the combined thickness of as many of said boxes as there are groups, the said sheet being provided with a plurality of

tongues on each side equal in number to the number of boxes which the display device is 25 adapted to hold, in combination with a plurality of individual boxes disposed transversely of the sheet which forms the display device, said boxes being equal in length to the width of the body of the sheet, each box 30 being in alinement with two of said oppositely disposed tongues and secured to the body of the sheet by the tongues being tucked into the ends of the boxes, said sheet being provided with a flap at one end and 35 means whereby when the sheet is folded and the several groups of boxes are folded together, the said flap may be engaged with the opposite end of the sheet.

In testimony whereof I affix my signature, 40 in presence of two witnesses.

FREDERICK C. ELY.
